07-405

EX
OR D 163

No. 163

For Dr Jones

Patent-148

Mr. G. Brown
Wooling Stone
Connecticut

Patent-148

Des. 163

Wm P. Cresson, David Stuart, Samuel H. Sailor & Jacob Bresley Philadelphia Co. Penn.^a
Letters Patent No 163 dated 18th January 1848.

(Assigned to Wm P. Cresson)

The Schedule referred to in these Letters Patent and making part of the same

To all whom it may concern: Be it known that we Wm P. Cresson David Stuart Samuel H. Sailor & Jacob Bresley all of the County of Philadelphia in the State of Pennsylvania have invented or produced a new and useful design which are intended to ornament a Cooking Stove, and do hereby declare that the following is a full and exact description of the same.

Fig. 1 represents the front plate, the edges of which are ornamented entirely around with a waisted edging or moulding as represented at a a a a, in close connexion with said moulding a Panel is raised relieved by a series of beading passing around it as represented at b b b the panel is ornamented nearly to the centre with a series of leaf and scroll work represented at c c c c

Fig. 2 represents the door of the oven the edges of this plate are ornamented with the same waisted moulding as Fig. 1 and represented at d d d d and in close connexion a Panel is raised and relieved by a series of Beading as represented at e e e e, the whole of the Panel is ornamented with a series of scroll and leaf work as represented at f f f f

Fig. 3 represents the Back Plate. It is ornamented around the edges with the same waisted moulding as Fig. 1 and 2 and represented at g g g g a short distance from the edges a Panel is formed by the beading represented at h h h h and a scolloped moulding represented at i i i and the centre is ornamented with scroll and leaf work represented at j.

Dec 16th 3

2

We have thus described the ornamental designs which we wish to Patent and do hereby claim the exclusive right to the same for the stove plates as we have laid them out and displayed them.

Witnesses

Richd Peterson. }
 Jas. M. Wills

Wm P. Cresson Eng
 J. H. Sailor Ill
 Jacob Beesley
 David Stuart
 481 words